UNITED STATES PATENT OFFICE.

CHARLES E. POPE, OF HOLYOKE, MASSACHUSETTS.

METHOD AND MACHINE FOR MAKING PAPER.

Specification of Letters Patent. Patented May 25, 1915.

1,140,711.

Application filed February 19, 1914. Serial No. 819,826.

To all whom it may concern:

Be it known that I, CHARLES E. POPE, a citizen of the United States, residing at Holyoke, in the county of Hampden and State of Massachusetts, have invented an Improvement in Methods and Machines for Making Paper, of which the following is a specification.

In paper-making machines, the felt passes between the first one or more sets of press-rolls and the web is carried between the press-rolls with and by the felt, and the tendency is for the web, when leaving the bite of said rolls, to follow the cylindrical surface of the upper press-roll, thus being removed from the felt, and winding upon said press-roll. In starting the machine after a break has occurred or after it has been stopped for any other reason, the web always or almost always sticks to the upper press-roll and follows it around to the usual doctor by which it is scraped from the roll and on which it masses in a hugh pile of waste until a highly skilled operative is able to remove the web by hand from the press-roll and stick it to the felt so that it will move with it. When this has been done successfully the pull of the web will ordinarily be sufficient to overcome the tendency for the web to stick to and wind upon the press-roll and thereby cause the web to follow the felt, so as to be moved with and by it. Whatever efforts may have been made to cause the web to leave the roll by other than manual means have not been sufficiently successful to displace manual methods. The difficulty is increased in proportion to the speed of the machine. At the present time machines are often run at a very high speed and efforts are being made constantly to increase the speed, with the result that the taking off of the web from the press-roll and carrying it to the felt, by a manual operation, notwithstanding the skill of the highly trained operator, is a serious problem. A machine cannot be run faster than it is possible to do this work.

This invention involves a novel method of taking off the web from the press-roll and carrying it to the felt; and also involves means for carrying out said method, which means is associated with the upper press-roll and is arranged adjacent the felt by which the web is taken off of said roll and carried

to the felt, and the well-known manual operation thereby dispensed with.

In the embodiment of my invention here shown for illustration, means are provided for forcibly delivering a thin sheet of air substantially tangential to the cylindrical surface of the press-roll, which is directed downward or toward the felt, thereby to take off the web from the press-roll (in case it should have a tendency to adhere thereto or to wind thereon) and carry it to the felt. The pneumatic take-off device here shown by which such thin sheet of air is delivered may consist of a hollow shell or case, more or less triangular in longitudinal vertical section, having converging upper and under sides and inclosed ends and having a narrow slot or passage at the apex of the triangle which is extended across the width of the shell or case, and said shell or case is supported by suitable means adjacent the press-roll with its apex pointed in a direction substantially tangential to the cylindrical surface thereof, so that a thin sheet of air which issues, when desired, from the slot or passage, is directed substantially tangentially against said cylindrical surface and in a direction toward the felt, thereby to take off or blow off the web from the roll so that it will pass to the felt. Said shell or case will be connected with any suitable air-forcing device by which the air will be delivered thereto under a suitable pressure, in order that it may be caused to forcibly issue therefrom.

Figure 1 shows, in conventional form, a portion of a paper-making machine having means for taking off the web from the press-roll and carrying it to the felt. Fig. 2 is an enlarged plan view of the hollow shell or case with slotted end-portion by which a thin sheet of air is forcibly delivered substantially tangential to the cylindrical surface of the press-roll. Fig. 3 is a longitudinal vertical section of said hollow shell or case.

Referring to the drawing of the machine here shown, 10 represents the usual felt passing over the usual rolls 12; and 13, 14 represent one pair of press-rolls, it being understood that the machine has or may have several felts and several pairs of press-rolls, all as usual in Fourdrinier or other forms of paper-making machines.

15 represents a hollow shell or case of approximately triangular form in longitudinal vertical section, it having converging upper and under sides and inclosed ends. The 5 shape of the ends is here shown as parallel, but is not important. Said shell or case has at its apex a long narrow slot or passage 16, extending as far as desired across its width, through which a thin sheet of air 10 is caused to issue, when desired, at any desired pressure. This slot need not be continuous. Said shell or case is connected at one side of its larger end-portion with a pipe 20, which latter is in open communication 15 with the shell or case, and is connected with a suitable air-forcing apparatus or compressed air system, by which air under pressure is delivered to the shell or case. Another pipe 21 is connected with the other 20 side of the shell or case, opposite the pipe 20, which is likewise in open communication with the shell or case and has connected with it a pressure-gage. Said shell or case is preferably so connected with said pipes 25 20 and 21, that it may be swung thereon, as pivots, although in lieu thereof it may be otherwise pivotally or movably or even immovably supported. Said shell or case is arranged adjacent the upper press-roll and 30 as here shown its converging end-portion is arranged approximately tangential to the cylindrical surface thereof, so that the thin sheet of air which is caused to issue forcibly from the slot or passage in its apex is 35 directed tangentially, or nearly so, to the cylindrical surface of said roll, and in a downward direction, in order that the web may be taken off of the roll and carried to the felt. The shell or case is preferably 40 made movable in order that it may be swung into and out of position for use when desired, although it may be permanently or stationarily supported if desired. The dotted lines in Fig. 1 show the shell or case 45 swung downward. It is obvious that by swinging the shell or case the direction of issuance of the thin sheet of air may be varied as desired, according to the extent of the swinging movement. 50 The pipe-system is provided preferably with a regulating-cock 25, whereby the supply and pressure of air may be regulated, and in case it is desired said cock may be turned to entirely shut off the supply of air. 55 This provision also enables the device to be used temporarily or permanently.

In operation I arrange the pneumatic take-off device in position so that the thin sheet of air will be directed approximately 60 tangential against the cylindrical surface of the press-roll, so as to separate the web from the roll and then admit air to the device at a proper pressure. This pressure may be varied within very wide limits, but very 65 slight pressure is sufficient. Less than four

pounds will do the work in any ordinary machine, but if this pressure is found insufficient, greater pressure may be employed without harm. The pneumatic take-off device may be arranged in actual contact with 70 the upper press-roll if desired, but such contact is not necessary, and I prefer to maintain the device a fraction of an inch from the press-roll. It is not necessary to direct the air tangentially with exactness 75 but only to direct the air so that it will force itself between the roll and the web and peel the web from the roll and cause it to pass to or fall on the felt. When the pneumatic take-off device is in position, with 80 the air issuing at the proper force and directed in the proper manner, a narrow strip of the web is allowed to pass from the Fourdrinier wire onto the felt and between the press-rolls. This end-portion will, in sub- 85 stantially all cases, follow the upper press-roll until it is met by the current of air from the take-off device, which will immediately peel it from the press-roll and cause it to pass or drop onto the felt and be carried 90 along thereby. The width of the web coming from the Fourdrinier wire may then be gradually increased to its full extent and it will follow along on the felt, being led along by the part already thereon. 95

The foregoing is the simplest method of operating the device, but the order in which the foregoing steps are given need not be followed, as the thin sheet of air, if given sufficient force, will cut the web and drive it 100 away from the upper press-roll, even if the web is started before the air blast, so that the web, before the air is turned on, has passed beyond the pneumatic take-off device. It will be necessary, however, to use 105 more air pressure to cut the web after the end of the web has passed the pneumatic take-off device than to peel off the end-portion of the web, and accordingly, I prefer to so arrange the operation that the pneumatic take-off device operates against an 110 end-portion of the web and not in such a manner that it is necessary for the sheet of air to cut the web being wound around the press-roll. After the full width of paper is 115 running properly the air blast should ordinarily be stopped, as unnecessary, but if any tendency to stick to the roll appears the necessary blast may be continued permanently or as long as desired. 120

In paper-making it is such a general custom to start a narrow strip of web from the Fourdrinier wire onto the felts that my apparatus is made quite narrow, as compared with the width of the machine, particularly 125 to operate on such a narrow portion, but my device is not limited to a narrow pneumatic take-off device. A pneumatic take-off device constructed as above described, but extending the entire width of the press-roll, 130

though unnecessarily expensive in construction and operation, would be entirely within the spirit of my invention, and in case of an exceedingly delicate web, or other peculiar condition, might be preferred; but for practical purposes a width of say ten inches for the pneumatic take-off device will be sufficient. I also prefer to have the device arranged at one end of the press-roll, as being more convenient.

10 My invention may be applied to any of the press-rolls in substantially the same manner as herein shown for the first press-roll.

15 I have herein referred to the use of a sheet of air, that being the most convenient gas to use, but steam or any other suitable gas may be used if desired without departing from my invention and the term air is 20 to be understood to include such suitable gas.

I claim:-

1. A Fourdrinier paper-making machine having in combination an upper press-roll 25 and felt, and pneumatic means arranged to remove the web adhering to the press-roll and carry it to the felt, substantially as described.

2. A Fourdrinier paper-making machine 30 having in combination an upper press-roll and felt, and pneumatic means arranged to forcibly deliver a current of air against said press-roll in a direction toward the felt, substantially as described.

3. A Fourdrinier paper-making machine 35 having in combination a rotatable press-roll and a felt in moving engagement with said roll, and means arranged to forcibly deliver a thin sheet of air substantially tangential 40 to the cylindrical surface of said roll, substantially as described.

4. A Fourdrinier paper-making machine having in combination a rotatable press-roll and a felt in moving engagement with said 45 roll, and means arranged to forcibly deliver a thin sheet of air substantially tangential to the cylindrical surface of said roll and in a direction toward the felt, substantially as described.

5. A Fourdrinier paper-making machine 50 having in combination a pair of rotatable press-rolls and a moving felt arranged between them, and means associated with the upper press-roll of the pair and arranged to 55 forcibly deliver a thin sheet of air substantially tangential to the cylindrical surface of said press-roll and in a direction toward the felt, substantially as described.

6. A Fourdrinier paper-making machine 60 having in combination a rotatable press-roll and a felt in moving engagement with said press-roll, and means to forcibly deliver a thin sheet of air substantially tangential to the cylindrical surface of said roll, said 65 means being movable to vary the direction

of issuance of said thin sheet of air, substantially as described.

7. A Fourdrinier paper-making machine having in combination a rotatable press-roll 70 and a felt in moving engagement with said press-roll, and means arranged to forcibly deliver a thin sheet of air substantially tangential to the cylindrical surface of said roll, said means being pivotally supported, substantially as described.

75 8. A Fourdrinier paper-making machine having in combination a rotatable press-roll, a felt in moving engagement with said roll, and a hollow shell in open communication with an air supply, said shell having a long 80 narrow slot arranged to deliver a thin sheet of air, and said shell being arranged adjacent the press-roll, whereby said thin sheet of air is delivered substantially tangential 85 to the cylindrical surface of said roll, substantially as described.

9. A Fourdrinier paper-making machine having in combination a rotatable press-roll, a felt in moving engagement with said roll, and a hollow shell of triangular form in 90 longitudinal vertical section, in open communication with an air supply, said shell having a long narrow slot at its apex, and said shell being arranged with its slot adjacent said press-roll whereby a thin sheet of air is delivered substantially tangential 95 to the cylindrical surface of said roll, substantially as described.

10. A Fourdrinier paper-making machine 100 having in combination a rotatable press-roll, a felt in moving engagement with said roll, and a hollow shell movably supported and in open communication with an air supply, said shell having a long narrow slot arranged 105 to deliver a thin sheet of air, and said shell being arranged adjacent the press-roll, whereby said thin sheet of air is delivered substantially tangential to the cylindrical surface of said roll, substantially as described.

11. A Fourdrinier paper-making machine 110 having in combination a rotatable press-roll, a felt in moving engagement with said roll, and hollow shell having openings at its ends and pipes arranged in said openings which are connected with an air supply, said shell having a long narrow slot for the delivery 115 of a thin sheet of air and said shell being located adjacent the press-roll with its slot arranged to deliver a thin sheet of air substantially tangential to the cylindrical surface of said roll and in a direction toward the felt, substantially as described.

12. A Fourdrinier paper-making machine 125 having in combination rotatable press-rolls, a web-carrying felt passing between them, a pneumatic device arranged to direct a thin sheet of air between the upper press-roll and a web in contact with said roll, to prevent 130 the web from winding on said roll and to

direct it toward the felt on which it is carried, said device being movable whereby the direction of issuance of the current of air may be varied, and means for adjusting the force of the current of air, substantially as described.

13. The pneumatic take-off device for the upper press-roll of a Fourdrinier paper-making machine, consisting of a hollow shell 10 arranged for connection with a compressed air supply, and having an exit orifice for the delivering of a thin sheet of air, substantially as described.

14. That improvement in the art of making paper upon a Fourdrinier paper making machine which consists in directing a thin sheet of air tangential to the cylindrical surface of the press-roll and toward the felt, which is in moving engagement with 20 said press-roll with force sufficient to take

off the web from said roll and carry it to the felt, and prevent it from winding on the press-roll.

15. That improvement in the art of making paper upon a Fourdrinier paper making machine which consists in directing a thin sheet of air with considerable velocity, tangential to the cylindrical surface of the press-roll, and toward the felt which is in moving engagement with said press-roll, 25 thereby to cause the web to maintain its engagement with the felt and prevent it from winding on the press-roll.

In testimony whereof, I have signed my name to this specification, in the presence of 30 two subscribing witnesses.

CHARLES E. POPE.
